HANDLE FOR A VALVE OR THE LIKE

Robert H. Dawson, Chicago, Ill., assignor to The Imperial Brass Manufacturing Company, a corporation of Illinois

Application March 2, 1955, Serial No. 34,831

Term of patent 7 years

(Cl. D78—1)

Fig. 1 is a top plan view of a handle for a valve or the like, showing my new design.

Fig. 2 is a side elevational view taken from the bottom in Fig. 1.

Fig. 3 is a side elevational view taken from the side in Fig. 1.

I claim:

The ornamental design for a handle for a valve or the like, as shown.
